UNITED STATES PATENT OFFICE.

WONG I. GONG, OF NEW YORK, N. Y.

CLOTHES-WRINGER.

SPECIFICATION forming part of Letters Patent No. 510,171, dated December 5, 1893.

Application filed March 24, 1893. Serial No. 467,431. (No model.)

To all whom it may concern:

Be it known that I, WONG I. GONG, residing in the city and county of New York, in the State of New York, have invented a new 5 and useful Improvement in Clothes-Wringers, of which the following is a specification.

My improvement relates to the springs. I will show the invention as applied with ash or other elastic wood springs. I reinforce 10 their action with soft vulcanized rubber applied in a form adapted to give more than the usual range of action. The rubber is molded in a form of hollow cylinders which are laid on their sides in nearly corresponding cavities in bearing boxes, which latter are provided with a fair bearing on the adjacent surfaces of the wood. The hollow cylinders are flattened more or less under the varying strains to allow the required yielding action. 15 One of these hollow cylinders thus mounted will suffice for small wringers. I prefer two for the larger sizes. Three may be used in extreme cases.

My invention develops nearly uniform action in the rubber. When the rolls are in contact, the rubber will distend to very nearly a cylindrical form; when the wringer takes a thick mass and the rolls are forced apart by the yielding of the springs, the hollow cylinders of rubber, become flattened and contribute much to the yielding action while only slightly increasing the tension of the springs. 20

The accompanying drawings form a part of this specification and represent what I consider the best means of carrying out the invention.

Figure 1 is a face view of the wringer having my invention with two of the hollow cylinders. Fig. 2 is a vertical section on the line 25 2—2 in Fig. 1. The remaining figures are on a larger scale. Fig. 3 is a face view of my hollow rubber cylinders and their inclosing box detached. Fig. 4 is a vertical section. Fig. 5 is a perspective view of the lower box, and Fig. 6 is a perspective view of one of my hollow cylinders detached.

Similar letters of reference indicate corresponding parts in all the figures where they appear.

A is the framing of the wringer, B and C 50 the rollers, and D, D, the thumb-screws which adjust the pressure of the springs urging the rolls together.

E, F, are wooden springs receiving the force of the screws and transmitting it to the boxes 55 G which press on the journals of the upper roller.

I, I, are boxes of hard wood or metal, having nearly semi-cylindrical cavities in their faces and having, at the back of each, flanges 60 I' which are let into the springs at each side in their mid-length and keep the boxes reliably in place.

J, J, are hollow cylinders of soft vulcanized rubber inclosed in the nearly semi-cylindrical 65 cavities in the boxes. The construction allows these hollow cylinders to flatten under a great pressure and to again resume their cylindrical form as the pressure is relaxed.

The form of the rubber gives a reliable 70 and approximately uniform action under the greatly varying pressures to which it is subjected in practice. The flanges I' being let into the wood resist displacement of the boxes either transversely or longitudinally without 75 appreciably weakening the spring.

I claim as my invention—

In a clothes-wringer, the boxes I, having flanges I' and rounded cavities in combination with the wood springs E, F, recessed to 80 receive said flanges, and with a soft rubber spring J in the form of a hollow cylinder inclosed in such cavities, all arranged to serve as herein specified.

In testimony that I claim the invention 85 above set forth I affix my signature in presence of two witnesses.

WONG I. GONG.
